UNITED STATES PATENT OFFICE.

GUSTAV R. KELM, OF NEW YORK, N. Y., ASSIGNOR TO WALKER M. LEVETT COMPANY, OF NEW YORK, N. Y., A CORPORATION OF NEW YORK.

PISTON.

Application filed May 18, 1921, Serial No. 470,502. Renewed September 15, 1923.

This invention relates to pistons for internal combustion engines, and particularly to pistons having a skirt which is expansible which is adapted to have a snug sliding fit in the cylinder when cold. Upon expansion of the piston the skirt will engage the cylinder without sticking in the cylinder, and after the cylinder has also expanded will again automatically expand and take up the free play between the cylinder and piston, which would otherwise occur.

Certain pistons of this type have been constructed in which the sleeve or skirt is divided into longitudinal sections, by means of longitudinal slits or cuts, the opposed sections in which the piston pin bosses are positioned being integrally connected to the piston head, and the remaining sections being separated from the head by circumferential slots or cuts and held in proper relation to the other sections by means of webs extending from each pin boss section to the other sections, interiorly of the skirt. Heretofore these webs have been straight and have been cast integral with the ends of the respective hollow inwardly projecting piston pin bosses, and each web has extended to and has joined intermediate skirt sections on lines which are chords of the skirt circle. In such a construction each web holds rigidly apart portions of the opposed skirt sections to which its ends are respectively joined, and permits the other portions of such section to expand and contract unequally because of the angle at which the web joins the sections.

To overcome this objection in pistons of the kind referred to is one of the objects of my invention.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of invention:

Figure 1 is an elevation of a piston embodying my invention;

Figure 2 is a bottom plan view of the same.

Figure 3 is a longitudinal view, taken on the line 3-3 of Figure 2; and

Figure 4 is a longitudinal view taken on the line 4-4 of Figure 2.

Referring to the drawings, 5 indicates the head portion of a piston, 6 the portions of the skirt within which the piston pin bosses 10 lie and to which they may be attached at or near their outer extremities. The skirt portions 6 may be separated by longitudinal cuts or slits 7 from the portions 8 of the skirt intermediate the bosses 10. The skirt, preferably intermediate the bosses 10, is separated from the head 5 by circumferential slots 9. The piston pin bosses 10 are integrally connected with the head portion 5 and project inwardly through transversely arranged webs 11 which extend to and are integral with the skirt intermediate the piston pin bosses 10. Each web 11 is inherently a spring and preferably has a curved or bent part 12 between the boss 10 and the point at which it joins the inner face of the skirt. It has been found desirable to have the web at its juncture to the skirt arranged at a wide angle, approximating a right angle, and therefore does not act to affect the contraction or expansion of the skirt in the manner described above.

The webs are connected to the skirt in the plane of the piston bosses and preferably do not extend the full length of the skirt to which they are united.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

What I claim is:

1. In a piston construction an integral casting comprising a circumferentially grooved, ring receiving head and a skirt, said skirt comprising a plurality of diametrically opposed bearing slide segments the

outer faces of which are of curvilinear form and a pair of deep diametrically opposed inwardly curved supporting webs which include elastic portions, said webs extending between and connecting the edge portions of the slide segments, the said casting being circumferentially slit between the head and the slide bearing segments to permit expansive movement of the latter independently of the head and the bearing segments each being circumferentially incompressible between the connections of the webs thereto.

2. In a piston construction an integral casting comprising a circumferentially grooved, ring receiving head and a skirt, said skirt comprising a plurality of diametrically opposed bearing slide segments the outer faces of which are of curvilinear form and a pair of deep diametrically opposed inwardly curved supporting webs which include elastic portions, said webs extending between and connecting the edge portions of the slide segments at a wide angle, the said casting being circumferentially slit between the head and the

slide bearing segments to permit expansive movement of the latter independently of the head and the bearing segments each being circumferentially incompressible between the connections of the webs thereto.

3. In a piston construction an integral casting comprising a circumferentially grooved, ring receiving head and a skirt, said skirt comprising a plurality of diametrically opposed bearing slide segments the outer faces of which are of curvilinear form, each slide segment being circumferentially incompressible, a pair of deep diametrically opposed inwardly curved supporting webs which include elastic portions, said webs extending between and connecting the edge portions of the slide segments, the said casting being circumferentially slit between the head and the slide bearing segments to permit expansive movement of the latter independently of the head and the wrist pin bearing members carried by the material of the webs.

In testimony whereof I affix my signature.
GUSTAV R. KELM.
